UNITED STATES PATENT OFFICE.

HARRY S. ALEXANDER, OF CHICAGO, ILLINOIS, ASSIGNOR TO TATER-FLAKES COMPANY, OF CHICAGO, ILLINOIS, A CORPORATION OF ILLINOIS.

DISPLAY DEVICE.

Application filed January 2, 1926. Serial No. 78,761.

The present invention relates to a display device.

My display device is particularly adaptable for merchandising confections, nuts, 5 and other food products commonly sold in packages, although its use need not be limited to goods of this sort.

The devices now in use generally comprise a metal framework which is usually provided 10 with means for securing thereto the cards bearing the package goods to be sold. Such devices are not only cumbersome, but they are also expensive and relatively difficult to manufacture.

15 I provide a structure, the outstanding features of which are its simplicity and low manufacturing cost. My device comprises a box-shaped support member, the sides of which are provided with a plurality of openings. Adapted to cooperate with these openings are suitable laps which are formed integral with the cards bearing the goods to be sold. I also provide locking means for holding the cards securely to the support so that 20 they will not be pulled off when packages 25 are removed therefrom.

The above and other novel features of the invention will be set forth more fully in the following specification when taken in connection with the accompanying drawings.

In the drawings:—

Fig. 1 is an isometric view of a display device of my invention;

30 Fig. 2 is a sectional view taken on line 2—2 of Fig. 1;

Fig. 3 is a development of the box-shaped support member;

Fig. 4 is a development of the end pieces 40 for the support member; and

Fig. 5 is a front view of the mounting board or card to which the packages containing goods to be sold are secured.

In the preferred form of my invention, I 45 provide a box-shaped support member which is generally designated in the drawings by the numeral 10. The developed view of this member illustrated in Fig. 3, shows it as having four sides. However, I wish it understood that it may have any number of sides and that four have been employed simply to show the manner of constructing and using my invention. These sides are designated by the numeral 11 and are generally 50 rectangular in form. Each one of them is

provided with a plurality of slots, in this case five in each side, 12, which are preferably spaced equally from each other. From the description which follows, it will be seen that any number of slots may be used, and 55 that these may be separated at various distances from one another. The support member 10 may be made of fiber, cardboard, or other material of a similar nature. The sides 11 are formed by bending the cardboard along the dotted lines 13. A lap 14 which may be either secured to the adjacent side by means of glue or suitable clips, serves to hold the sides in their folded position. The upper and lower ends of the support 60 member 10, are covered by means of suitable end pieces 15. Each end piece is provided with laps 16 by means of which it is fastened to the sides 11. Centrally disposed in each end piece 15 are openings 17. A 65 metal eyelet 18 is permanently fastened in each opening 17 and serves as a bearing member for the shaft 19 on which the support 10 is mounted. The shaft 19 is threaded at its lower end. These threads are 70 adapted to cooperate with similar threads in a threaded opening provided therefor in the metal base 20. To keep the support member 10 a suitable distance above the base 20, I strike lugs 21 out of the shaft 19, on 75 which the eyelet in the bottom end piece is adapted to rest. Hence, it will be observed that this structure permits free rotatable movement of the support member 10 about the shaft 19.

80 Adapted to fit over the outer surface of each side 11 are the mounting boards or card 22. These may also be made of fiber, cardboard, or the like. Each mounting board is provided with a plurality of V-shaped laps or tongues, in this case five in 85 number. Starting with the lap 23 at the top of the card shown in Fig. 5, it will be noted that each of the succeeding laps 24, 25, 26 and 27, is longer than the preceding one. 90 The width across the top of each of the laps 23, 24, 25 and 26, is the same. These laps are formed by simply cutting out the edges which form each V from a point on the central longitudinal axis of the card to the 95 dotted lines 30. These are spaced from each other the same distance that the corresponding laps 12 are spaced from each other on the sides 11. The widths of the laps across their upper edges are slightly less than the 100 105 110

width of the slots 12 with which the respective laps are to cooperate. The lap 27 is of a different structure. Although the edges are cut from a point starting on the central longitudinal axis of the card 22, they do not extend upwardly so as to form an isosceles triangle, as in the case of the other laps. This lap is set over to one side and has a portion cut away therefrom so as to form an opening 28 in the card 22. This leaves a jog 29 in the lap 27, the purpose of which will be hereinafter explained. The length of the lap 27 is also greater than any one of the preceding laps. The spacing, however, between it and the preceding lap is the same as it is between the other laps.

To illustrate one feature of my invention, let us suppose that each lap is of the same general structure, except that every lap is longer than the preceding one, as shown. Now, if the lap 27 is brought into cooperation with the lower slot in one of the side members 11, the remaining laps, with the possible exception of the lap adjacent the lap 27, will still be free of the slots 12. Now, as the card 22 is brought closer to the side 11, on which it is to be mounted, the remaining laps will engage with their respective slots. The purpose, therefore, of making each succeeding lap longer than the preceding one, is to permit easy mounting of the card on the member 10. However, I find that if no means were provided for holding the card in place, once it is placed on the member 10, that removal of one of the packages secured to the card would also cause the card to be pulled out of engagement with the mounting member. To avoid this, I provide a locking means on one of the laps. In this case, the locking means is shown in connection with the lap 27. When this lap is inserted into its cooperating slot 12, the jog 29 thereof will engage with the upper edge of the slot 12. Now, if the car is pulled upward, as is done when a package is re-

moved therefrom, it will be impossible to move it away from the side with which it is in contact. The only way this can be done is by freeing the portion 29 from the upper edge of the slot 12.

From the foregoing, it will be seen that the invention is not limited to the use of five slots in each side and a corresponding number of V-shaped laps on each mounting board, as any number of slots and V-shaped laps cooperating therewith may be used. Nor is it necessary to have V-shaped laps, or laps of any other shape, which have been formed out of the mounting board itself. Separate laps may be used and these may be glued or otherwise fastened to the mounting board in any desirable manner.

I claim:

1. In a device of the character described, a vertical support of sheet material provided with a plurality of horizontal slots arranged in a vertical series, and a mounting board having a plurality of tongues extending therefrom and engaging through said slots, one of said tongues having an element normally disposed beneath the upper wall of its cooperating slot and coacting therewith to prevent casual removal of the board from the support.

2. In a device of the character described, a vertical support of sheet material provided with a plurality of aligned horizontal slots arranged in a vertical series, and a mounting board having a plurality of tongues extending therefrom and engaging through said slots, one of said tongues being disposed out of alignment with the other tongues and having its upper portion shaped to provide an element disposed for engagement beneath the adjacent corner portion of the top wall of its cooperating slot.

In witness whereof, I hereunto subscribe my name this 30th day of December, 1925.

HARRY S. ALEXANDER.
